UNITED STATES PATENT OFFICE.

PHILLIP WAGNER, OF EARL GREY, SASKATCHEWAN, CANADA.

GRAIN-SHOCKER.

1,331,224.

Specification of Letters Patent. Patented Feb. 17, 1920.

Application filed April 9, 1918. Serial No. 227,547.

To all whom it may concern:

Be it known that I, PHILLIP WAGNER, a citizen of the Russian Republic, residing at the town of Earl Grey, in the Province of 5 Saskatchewan, Dominion of Canada, have invented certain new and useful Improvements in Grain-Shockers, of which the following is a specification.

This invention relates to improvements in 10 grain shockers, and the objects of the invention are to facilitate forming a shock mechanically and automatically dumping the same in the manner best calculated to form a proper shock, to permit of the heads of the 15 sheaves being bunched together during the dumping operation, to provide means whereby the shock forming element will be properly cleared from the shock when dumped, so that there is no possibility of any of the 20 sheaves becoming displaced and the shock consequently collapsing.

Further objects are to arrange the mechanism whereby the shock is formed to receive the sheaves in the proper manner, so that the 25 center or core of the shock will be primarily built or constructed of four sheaves, while the outer portion of the shock will be built of sheaves placed around the four said sheaves, to provide means adapted to support 30 the butt of the sheaves when forming the shock, so that the sheaves can not become displaced vertically, and thus when the dumping operation is performed the butts of the sheaves will lie in the same horizontal 35 plane, and permit the sheaves to take up the desired angle of inclination relatively to each other to constitute a proper shock.

Further objects still are to permit of the 40 sheaves being delivered to the shock forming element butts first, so that when the sheaves are thrown into a vertical position the heads will be uppermost, and generally to adapt the several parts of the machine to better perform the functions required of them.

45 With the above and other objects in view the invention consists essentially of the improved construction particularly described and set forth in the following specification and accompanying drawings forming part 50 of the same.

In the drawing,

Figure 1 is a fragmentary rear view of a binder showing the improved shocking device arranged stubbleward thereon.

55 Fig. 2 is a fragmentary plan view of the binder showing the shocker arranged stub-

bleward thereof, and the means for connecting the shocker to the binder.

Fig. 3 is a side elevation partly sectional of the improved shocker. 60

Fig. 4 is a fragmentary sectional elevation of the sheaf receiving basket showing the cam means controlling the action of the packers.

Fig. 5 is a fragmentary front elevation of 65 part of the shocker showing the flexible means controlling the forward motion of the plate slidably mounted below the deck.

Fig. 6 is a fragmentary sectional elevation 70 of the plate retaining or locking means, and showing the co-acting cam designed to release the locking means and permit of the plate being retracted.

Like characters of reference refer to like parts in the several figures. 75

Referring to the drawings, A represents a binder of any usual description provided with the deck 10 and knotting mechanism 11, and having the usual tongue 12 to which horse traction may be attached.

80 The shocker or stooker is arranged stubbleward of the binder deck 10 and consists of a frame 13 formed with a deck 14 having rearwardly extending side members 15 carrying stub axles 16 on which the ground wheels 17 are rotatably mounted. On the front of the frame 13 and below the same a fork 18 is pivotally mounted and carries a guide wheel 19 rotatably mounted thereon and adapted to engage with the ground. 90

The rear of the deck 14 is cut away forming a substantially U-shaped recess 20 in which one of the baskets 21, designed to receive the sheaves, will be normally located as the sheaves are being delivered to the said 95 basket.

Around the front edge of the U-shaped portion 20 an upwardly extending flange 22 extends.

The side members 15 carry standards 23 100 in which the trunnions 24 of the skeleton rectangular frame 25 are rotatably mounted and the transverse arms of the said skeleton frame are each designed to support a sheaf receiving basket 21.

105 It will be seen that two baskets are employed, one of which will be in commission, while the other is out of commission, so that while one basket is being dumped the other will be brought into position to receive the 110 sheaves from the binder A.

Each of the transverse arms of the frame

25 carries a transversely extending plate 26 formed with journals 27 on the ends thereon, which rotatably engage with the said arms, and from this plate 26 the sheaf collecting basket 21 is hung.

This basket comprises a center spindle 28 rotatably supported from the plate 26, and provided with a plurality of radially extending arms 29, each of which is formed with 10 a plurality of downwardly extending rods or fingers 30, subdividing the basket into sheaf receiving compartments, and the outermost fingers are embraced by a circular band 31, which is rigidly attached thereto.

15 By referring to Fig. 2 the rearmost basket discloses the formation of the arms and fingers, and it will be seen that while four of the arms have fingers or rods 30 depending therefrom and extending from the inner to 20 the outer end of the arm, the other four intermediate arms have only two fingers extending therefrom at the outer end, so that the first four arms with their depending fingers are adapted to receive the four 25 sheaves which constitute the core of the shock, while the eight peripheral compartments located between consecutive arms will receive the remaining eight sheaves forming the outer portion of the shock.

30 The arms 29 carry a circular rod 32 on which the packing arms 33 are hinged adjacent to the top thereof, and these packing arms are provided with offset ends 34 on which rollers 35 are rotatably mounted.

35 These packing arms 33 are designed to be periodically rotated about their hinged point, and to permit of this operation taking place, I provide a cam race 36 pivotably attached to the plate 26 toward the rear

40 thereof, the front of the race being connected by a spring 37 to a hook or arm 38 extending upwardly and forwardly of the front of the said plate.

45 As the basket 21 is rotated in a horizontal plane, the rollers 35 of the packing arms 33 will consecutively engage the cam race 36 and so rotate the packing arms about their hinged points. All the packing arms are preferably closed during the dumping of the 50 shock, and the cam 39 which is mounted on the transverse arm of the frame 25 and operated through the orifice 40 in the plate 26 is rotated during the dumping operation and allows the race 36 to be rotated upwardly by the spring 37 thereby freeing the 55 roller 35 of the last open packing arms 33, which will thus close on the sheaf by gravity.

On the ends of the trunnions 24 disks 41 are rigidly mounted, which are provided 60 with arcuate racks 42, arranged diametrically opposite each other, the intervening portion of the periphery of the disk between the racks being smooth.

The disks 41 carry a guide plate 43, which 65 is supported from the outer face of the disk

by the brackets 44 and in this guide a block 45 is slidably mounted.

Adjacent to the disk 41, but located below the same, a gear 46 is rotatably mounted on a stub spindle 47, carried by the standards 23, and adjacent to this gear and connected thereto is a sprocket 48, which is connected through the chain 49 with a sprocket 50 mounted on the end of the transversely extending shaft 51, journaled in bearing on 75 the standard 23.

This shaft 51 is provided with a gear 52 which meshes with a gear 53 rotatably mounted on the stub spindle 54, and the gear 53 is formed integral with a sprocket 80 55, which is connected through a chain 56 with a sprocket 57 formed on the hub and adjacent to the brake band 58 of the ground wheel 17.

85 It will thus be seen that on forward movement of the machine, the rotary motion of the ground wheel 17 will be transmitted through the sprocket 57, chain 56 and sprocket 55 to the gear 53, which meshing with the gear 52 rotates the shaft 51. 90

This shaft 51 is provided intermediate of its length with a sprocket 59, which is connected through a chain 60 to a sprocket 61 carried by the transversely extending spindle 62 of the conveyer 63, rotatably mounted in the open bottom of the hopper 64.

The hopper 64 is supported at the rear end by a bracket 65 from the deck 14, while the front of the hopper is supported from the standards 23 and is formed so that it 100 will overhang the shaft 51, and the discharge end of the hopper terminates adjacent to but above the front end of the U-shaped opening 20 in the deck.

On that end of the spindle 62, remote 105 from the sprocket 61, a beveled gear 66 is mounted, which meshes with the beveled gear 67 on the vertically disposed shaft 68, which is provided on the upper end with a beveled gear 69, designed to mesh with the 110 beveled gear 70, mounted on a spindle 71 of the angularly disposed conveyer 72.

One of the side walls of the hopper 64 is cut away as shown at 73 to receive the upper 115 end of the conveyer 72, and the sheaves delivered to the said conveyer will thus be deposited in the hopper 64.

On one side of the conveyer 72 an offset guide plate 73^a is provided, which is adapted to engage with the sheaves in such a 120 manner that the head of the sheaf will be delivered toward the rear, and the butt of the sheaf toward the front end of the hopper 64, and the sheaf is thus delivered to the baskets 21 butt first. 125

The sheaf receiving baskets 21 are rotated by a pair of levers 74 and 75, which engage with the outermost fingers 30 on the arms 29, and the levers are designed to be rotated in a substantially horizontal plane. The 130

movement of the lever 74 is continuous, while the movement of the lever 75 is intermittent.

The lever 74 is rigidly attached to a vertically disposed spindle 74^a carrying a gear 76, which meshes with a gear 77 rigidly mounted on the spindle rotatably journaled in the bearing 78 mounted on the deck 14, and the bracket 79 also carried by the said deck.

This gear is provided on the upper face with a peripheral, vertically disposed, arcuate flange 80, the ends of which are beveled, the flange being formed on a segment 15 of the gear and during the rotation of the gear intermittently engages with the resilient bracket 81, the lower end of which is rigidly attached to the deck 14, while the upper end is offset and embraces the spindle 20 74^a.

The lever 75 is loosely mounted on the spindle 74^a, and the said lever is provided on its shorter arm with an upwardly offset end 82, which, when the flange 80 engages 25 with the resilient bracket 81, moves the lever 75 bodily upwardly and so engages the offset end 82 with the lever 74, so that both levers 74 and 75 under such circumstances will be rotated simultaneously.

As the levers are arranged in alignment to each other, they will be alternately engaged with the outer fingers 30 of the baskets 21, so that for each revolution of the 30 levers, the baskets will be rotated through two sheaf receiving compartments.

The spindle 74^a is provided on the lower end with a beveled gear 83 adapted to mesh with the gear 84 rigidly mounted on one 40 end of the shaft 85, which is rotatably supported in journals from the deck 14, while the opposite end of the said shaft is provided with a beveled gear 86 adapted to mesh with the gear 87 mounted on one end of the longitudinal shaft 88.

This shaft 88 is rotatably supported in bearings from the deck 14, and is provided at the opposite end with a gear 89 adapted to mesh with the gear 90 carried by the shaft 91.

The shaft 91 is journaled at one end in a bearing mounted on the deck 14, and is provided intermediate of its length with a universal joint 92, while on the opposite end of the shaft a gear 93 is mounted adapted to 55 mesh with a beveled gear 94 on the end of the shaft of the knotting mechanism 11.

The frame 13 is connected to the frame of the binder by a rod 95 and a spring 96 extends from intermediate of the length of 60 this rod to the said frame so that when the machine is passing around a corner, or taking a turn, there will be sufficient spring to prevent the machine being subjected to excessive or undue stress.

The front of the frame 13 is connected to

the tongue 12 by the rod 97, which is connected intermediate of its length to the said frame by the spring 98, which also permits of sufficient flexibility being given to the connection to allow the machine to take a 70 turn with ease.

The gear 77 is designed to perform another function beside that described above, and is provided on the lower face with a cam or wedge piece 99, which is adapted to 75 coact with the upwardly extending arm 100 of a Z-shaped lever, which is pivotally connected intermediate of its length to the deck 14, the downwardly extending arm 101 of the said lever extending through an orifice 80 102 in the deck and engaging with the front end of the plate 103 to normally hold the same below the basket 21 being filled with sheaves.

The Z-shaped lever is engaged by the 85 leaf spring 104 which normally presses the arm 101 of the lever downwardly and holds it in intimate engagement with the plate 103.

This plate 103 is provided with rollers 105, which run in the channel guides 106 90 on the frame 13, and springs 107 are connected at one end to the said plate and at the other end are anchored to the front and under side of the deck 14.

As the arm 101 of the Z-shaped lever becomes disengaged from the plate 103, the plate is moved forwardly under the action of the springs 107 thereby leaving a clear space to permit of the dumping operation of the baskets 21 being carried out.

The plate 103 is designed to be moved rearwardly by flexible members 108, which are connected at one end to the said plate, and after passing through guides 109 are connected at the upper ends to pins 110, 105 carried by the sliding blocks 45.

As the frame 25, carrying the baskets 21, rotates on its trunnion 24, the guides 43 will be rotated with the disks 41 and a pull will be transmitted to the flexible members 110 108, and thus draw the said plate rearwardly, so that it will be located below the basket 21 being filled with sheaves, and retained in this position by the arm 101 of the Z-shaped lever until the basket has been 115 sufficiently filled with sheaves to be in a position ready for dumping.

Below the plate 103 a grid 111 is located, which is connected at its rear end by the links 112 to the front of the frame 13, the 120 said grid being supported intermediate of its length from the frame by means of the springs 113.

Around the circular band 31 of the baskets 21 a circular band 114 is loosely mounted and provided with pintles 115, which are connected to the lower ends of the links 116 hung from the transverse arms of the frame 25, so that the baskets cannot swing laterally.

- The pintles 115 engage with pairs of guide rods 116^a mounted on the sides of the standards 23 so that the circular band 114 suspended from the links 116 cannot be 5 swung rearwardly or forwardly, and lateral swinging of the band is also prevented since the band is just a good working fit between the guide rods located on the opposite standards.
- 10 The band 114 is consequently maintained in a horizontal position as also is the circular band 31 at the bottom of the basket which is embraced by the band 114. The basket will be held in a vertical position 15 during the operation of filling the basket and while free to be rotated in a horizontal plane during the filling operation is prevented from swinging.
- 15 The assembly of the machine will be 20 readily understood from the foregoing description. When the machine is in use and is being driven forwardly, the rotary motion of the ground wheels 17 is permitted through the sprockets 57 and 55, and chain 25 drive 56 to the gear 53, which meshes with the gear 52 and so rotates the shaft 51, which through the chain drive 60 and the gears 59 and 61 operate conveyer 63. This conveyer 63 operates the conveyer 72 30 by means of the intermeshing beveled gears 66 and 67, and 69 and 70 carried by the spindle 62, shaft 68 and spindle 71.
- 25 The shaft of the knotting mechanism 11 rotates the shaft 91 by means of the intermeshing gears 94 and 93, and this last said 35 shaft through the meshing gears 90 and 89 rotates the shaft 88, which in turn, through the gears 87 and 86, rotate the shaft 85. The shaft 85, through the meshing gears 84 40 and 83, rotates the spindle 74^a, and this rotates the lever 74 carried thereby.
- 30 The gear 76 on the spindle 74^a rotates the gear 77, and when the upper end of the 45 bracket 81 is about to engage the flange 80 of the gear 77, the forward basket 21, which will be in the lower position shown in Fig. 2, is ready to receive sheaves from the binder A.
- 35 The sheaves from the binder will be delivered to the conveyer 72, and the guide 50 plate 73^a will so dispose the heads of the sheaves, that they will be delivered first to the rear of the hopper 64, so that the butts of the sheaves will lie toward the front of 55 the hopper, and on being fed forwardly by the conveyer 63, the butts as they overhang the curvilinear front end of the hopper will be delivered into the lower end of the basket 21.
- 40 It is important to notice that in this position the packer plates 33 of that compartment of the basket 21, which is in alinement with and adjacent to the discharge end of the hopper 64 is raised for the reception of the 55 sheaf. The raising of this packing plate 65 33 is due to the roller 35 co-acting with the cam race 36.
- 45 The sheaf delivered to this compartment of the basket 21 will be deposited near the center of the basket and form one of the 60 core sheaves of the shock, the position of the sheaf being shown in dotted lines in the rear basket of Fig. 2, which is the only convenient place in which the position of this sheaf can be illustrated.
- 50 During the rotation of the spindle 74^a and while the upper end of the bracket 81 is in engagement with the flange 80, the lever 75 is raised to engage the lever 74, and both levers rotate and engage with the outermost fingers 30 of the baskets, which will be rotated during each revolution of the levers through two compartment divisions, so that in a first complete revolution of the basket 21 only four sheaves will be delivered 80 thereto, and will form the core sheaves of 85 the shock.
- 55 As the roller 35, carried by the packer 90 plates 33, engage with the cam race 36, each packer plate is rotated about its hinge point, and this leaves the compartment of the basket 21 in which it is located open for the reception of the sheaf, and after the sheaf has been delivered to the compartment the roller 35 becomes disengaged from the cam 95 race 36 and as a consequence the packer plate 33 rotates downwardly under gravity 100 into the compartment.
- 60 During the second revolution of the basket 21 the bracket 81 will have become 105 disengaged from the flange 80 with the result that the offset end 82 of the lever 75 will become disengaged from the lever 74, which alone will be rotated and engage with the outermost downwardly disposed fingers 105 30 of the arms of the basket 21 being filled with sheaves.
- 65 The basket 21 is consequently only moved through one compartment during each engagement of the lever 74, with the outermost fingers 30 of the basket, so that a sheaf is delivered to each of the compartments of the said baskets, and so builds up 110 the outer portion of the shock.
- 70 When the shock is ready for dumping, the wedge piece 99 engages the vertical arm 100 of the Z-shaped lever rotating the same 115 about its hinged point, and releasing the arm 101 from the plate 103, which will consequently be retracted under the pull of the 120 springs 107. The weight of the sheaves in the filled basket 21 will now tend to lower that basket, and thus rotate the frame 25 on its trunnions 24 and the butts of the sheaves will engage with the grid 111, thus 125 holding the sheaves in the proper position.
- 75 During the downward motion of the filled basket 21, the grid 111 will be forced down-

wardly until the butts of the sheaves engage the ground, and on the continued forward motion of the machine the basket 21 will free the sheaves and deposit them as a 5 shock, the heads of the outermost sheaves being held in place during this operation by the packer plates 33.

As the frame 25 rotates one of the racks 42 formed on the disks 41 will engage with 10 the gear 46, and the frame 25 will now be rotated on its trunnions 24 by the said gear which is driven through the sprocket 48, chain 49, and sprocket 50 on the shaft 51, which is in turn rotated by the intermeshing 15 gears 52 and 53, the latter of which is driven from a sprocket 55, chain 56 and sprocket 57 from the ground wheels 17.

As the frame 25 is rotated through a half revolution the basket which has just been 20 dumped will occupy an elevated position such as is illustrated in Fig. 2, while the empty basket, which was formerly in an elevated position, will now be in the lower position illustrated in said figure.

25 During this motion the pintles 115 engage the guides 116 on the standards 23 and so position the basket about to be filled relatively to the hopper 64.

During the rotation of the disks 41 the 30 guides 43 will also be rotated and after the dumping operation takes place a pull will be exerted on the flexible members 108 and draw the plate 103 rearwardly beneath the basket 21 now about to be filled, and when 35 the guides 43 have reached a vertical position, the blocks 45 will slide under gravity to the lower ends of the guides and thus give sufficient slack to the flexible members 108 to permit of the plate 103 being re- 40 tracted into its forward position when the arm 101 is disengaged therefrom.

It will be understood that when the plate 103 is drawn rearwardly the arm 101 of the Z-shaped lever will automatically engage 45 the said plate 103 and hold it in position under the basket 21 being filled, until the said basket is filled, when the said plate will be retracted in the manner above described preparatory to dumping the shock.

50 It will be seen by reference to Fig. 2 that one of the packer plates 33 will be slightly elevated when the dumping of the basket 21 is commenced but as soon as the frame 25 rotates, so that the lower end of the basket 55 reaches the ground, the cam 39 disengages with the cam race 36 and allows the roller 35 of the said packer plate to become disengaged with the cam race, so that the packer plate will close or rotate about its hinged 60 point under gravity.

The packer plates hold the heads of the sheaves in the proper position during the dumping and bunch them together.

From the above description it will be seen

that I have invented a shocker in which the 65 sheaves are built together and deposited on the ground in a manner best calculated to form a proper shock, the action of the several parts of the machine being automatic and so timed that there is no liability of 70 the shocks falling during dumping.

As many changes could be made in the above construction and many apparently 75 widely different embodiments of my invention within the scope of the claims, constructed, without departing from the spirit or scope thereof, it is intended that all matter contained in the accompanying specification and drawings shall be interpreted as illustrative and not in a limiting sense. 80

What I claim as my invention is:

1. A shocker of the class described comprising baskets extending rearwardly on the machine, means for rotating the baskets individually in a horizontal plane, and means 85 for rotating the baskets collectively in a vertical plane to dump the sheaves therein.

2. A shocker comprising baskets for the reception of sheaves, means for rotating the baskets in a horizontal plane, means for rotating the baskets collectively in a vertical plane, and packer plates carried by the 90 baskets designed to bunch the heads of the sheaves during dumping.

3. A shocker comprising sheaf receiving 95 baskets, packer plates carried by the baskets for bunching the sheaves during dumping, means for automatically elevating each packer plate during the reception of a sheaf to the basket, said packer plate being designed to close under gravity, and means 100 for dumping the basket.

4. A shocker comprising a rotatably supported frame, baskets supported from the transverse arms of the frame, means for rotating the baskets in a horizontal plane, and means for rotating the frame in a vertical plane. 105

5. A shocker comprising a rotatable frame, baskets hung from the said frame, means 110 for rotating the baskets individually in a horizontal plane, packer plates on the baskets, and cam means for successively elevating each of the packer plates during the rotation of the baskets for the reception of 115 sheaves.

6. A shocker comprising a vertical rotatable rectangular frame, baskets supported from the said frame, a cam race above the baskets, pivotally mounted packer plates on 120 the baskets having their upper ends designed to intermittently coat with the cam race and means for rotating the basket in a horizontal plane for the reception of sheaves.

7. A shocker comprising a vertical rotatable frame, cams on the transverse arms of the frame, a cam race pivotally supported below the transverse arms of the frame, bas- 125

kets hung from the frame, packer arms on the basket designed to engage the cam race, and means for disengaging the cam race from the packer arms during the rotation 5 of the frame.

8. A shocker comprising a basket for the reception of sheaves, means for rotating the basket in a horizontal plane to receive sheaves, a plate normally mounted below 10 the basket during the filling operation, automatic means for retracting the plate when the basket is filled, and means for rotating the basket in a vertical plane to automatically dump the same.

15. 9. A shocker comprising a cylindrical basket for the reception of sheaves, a frame supporting the basket, a band slidably engaging the lower end of the basket, links connecting the band and the frame, and 20 means for rotating the basket in a horizontal plane.

10. A shocker comprising a rotatable frame, a basket hung from the frame, a band slidably mounted on the lower end of 25 the basket provided with pintles, links connecting the pintles to the frame, guide means coacting with the pintles for the positioning of the basket for the reception of sheaves, and means for rotating the basket 30 in a horizontal plane.

11. A shocker comprising a basket subdivided into a plurality of compartments for the reception of sheaves, means for primarily rotating the basket in a horizontal 35 plane through a plurality of steps equal to two compartments to receive the core

sheaves of a shock, and means for subsequently rotating the basket through a plurality of steps equal to one compartment to receive the outer sheaves of the shocker. 40

12. A shocker comprising a basket subdivided into a plurality of compartments for the reception of sheaves, a pair of levers for rotating the basket in a horizontal plane, one of the levers being constantly 45 operated and the other being intermittently operated, and means for dumping the basket.

13. A shocker comprising a basket for the reception of sheaves, a pair of levers for 50 rotating the basket, one of the levers having an offset end, the other lever being constantly operative, and means for intermittently engaging the offset end of the first lever with the second lever to render the 55 first lever operative, and means for dumping the basket.

14. A shocker comprising a basket for the reception of the sheaves, means for rotating the basket in a horizontal plane, a hopper at the front of the basket, conveyer means operating in the bottom of the hopper, conveyer means arranged transversely to the said conveyer, guide means on the second conveyer whereby sheaves are delivered to the hopper with the butt adjacent to the basket, means for rotating the basket and means for dumping the basket. 60 65

In witness whereof I have hereunto set my hand.

PHILLIP WAGNER.
